**THREE-WAY INSULATED SPLICE FOR
ELECTRICAL CONDUCTORS****Herbert N. Steinmeyer, 2419 SW. Richardson,
Portland, Oreg. 97201**

Filed July 18, 1968, Ser. No. 12,817

Term of patent 14 years

Int. Cl. D13—03

U.S. CL. D26—1

FIG. 1**FIG. 2**

FIGURE 1 is a plan view of the design for a three-way insulated splice for conductors; and

FIGURE 2 is an edge view of the invention.

In the design, the upper and lower surfaces are identical. Also, the three extension portions are identical.

I claim:

The ornamental design for a three-way insulated splice for electrical conductors, as shown and described.
